UNITED STATES PATENT OFFICE.

CARL RUMPEL, OF BERLIN, AND HERMANN SCHRÖDER, OF BERLIN-WESTEND, GERMANY, ASSIGNORS TO THE FIRM OF SOMMER & RUNGE, OF BERLIN-FRIEDENAU, GERMANY.

ARTICULATOR.

Application filed May 14, 1923. Serial No. 638,868.

To all whom it may concern:

Be it known that we, Dr. CARL RUMPEL and Professor Dr. HERMANN SCHRÖDER, citizens of the Republic of Germany, residing at Berlin, and Berlin-Westend, Germany, respectively, have invented new and useful Improvements in Articulators, of which the following is a specification.

This invention relates to improvements in the articulator, a device employed in the dentistry for the production of artificial sets of teeth.

By means of the articulator it is attained to move the jaw-models of the patient against one another in the same way as the patient is used to do it when chewing. For this purpose firstly the chewing-moulds are obtained with the patient in known manner by the patient's chewing-motion. These chewing-moulds consist of a suitable wax-mass in which latter on performing the chewing-motion curved grooves are produced in the one of the wax-moulds by means of pins arranged in the other of the moulds.

The subject of the invention consists in the device of turnably arranged bearing- or guide-cases for the two ends of the articulator-axis so that the latter by the help of the chewing-moulds mentioned afore, which are placed into the articulator, is automatically moved by means of merely shifting the chewing-moulds one against the other along the curved guide-grooves in such manner as the virtual jaw-axis of the patient was moved when producing the wax-moulds, and whereby at the same time a guide-curve corresponding with the curves of the wax-mould is obtained for the adjustment-pin, for the purpose of avoiding in this way the measurements on the patient hitherto necessary for the adjustment of the articulator-axis, as such measurements can be executed with difficulty only and mostly lead to an inexact result.

A further subject of the invention consists in the arrangement of devices by means of which each of the two bearing- or guiding-cases of the articulator-axis can be fixed in any desired position.

Another subject of the invention consists in the arrangement of a turnable and fixable block within each of the two bearing-cases of the articulator-axis.

A still further subject of the invention consists in the arrangement of a pair of springy levers acting upon each of the ends of the articulator-axis at each of the two bearing-cases of the articulator-axis.

The drawing shows one form of carrying out the articulator with the aforesaid improvements.

Fig. 1 is a perspective view of the articulator. In the right-hand bearing-case the top-plate is omitted.

Fig. 2 is a vertical longitudinal section through one of the bearing- or guiding cases of the articulator-axis and the bearing appertaining thereto.

Fig. 3 is a vertical cross-section on the line A—B of Fig. 2.

Fig. 4 is a view of one of the bearing-cases of the articulator-axis with the bearing appertaining thereto and the top-plate taken off.

Fig. 5 is a view of the bearing-case with the top-plate taken off and with displaced block.

Fig. 6 is a view upon the front-plate of one of the bearing-cases for the articulator-axis.

Fig. 7 is a like view with the bearing-case placed in oblique position.

Fig. 8 is a vertical cross-section through the bearing-case according to C—D in Fig. 4. This figure shows the pair of springy levers provided at the inner side of the top-plate of the bearing-case.

Fig. 9 is an upper view of the articulator-axis with the arm fastened thereupon, the latter carrying the adjustment-pin, and the two bearing-cases of the articulator-axis. The front plates of the bearing-cases are shown in sectional representation. The dotted lines show the articulator-axis with the arm in a slightly turned position.

Fig. 10 is a like view as Fig. 9, but the articulator-axis is illustrated by dotted lines in a turned and simultaneously laterally displaced position and the bearing-cases as well as the blocks coming in contact with the ends of the articulator-axis are fixed in the position that corresponds with the respective position of the articulator-axis.

Figs. 9 and 10 are drawn in a somewhat reduced scale.

Upon the articulator-axis 1 the arm 3 carrying the adjustment-pin 2 is fastened. The

two ends of the articulator-axis are guided in the front-plates 4 of a semi-circular bearing-case 5, which is fastened on a pivot 6. This pivot is, by means of ball-bearing 7, positioned in a box 9 fastened on the stand 8 of the articulator and on account of the ball-bearing the pivot 6 is easily turnable. In the middle, the pivot 6 is surrounded by a ring 10 which however does not wholly span the pivot. By means of a screw 11 the ring 10 is secured against being turned. By way of a squeezing-screw 12 inserted into the box 9 from above, the ring 10 can be pressed firmly on the pivot 6 and thereby the pivot 6 can be made steadfast with the bearing-case 5 in the desired position.

The bearing-case 5 consists of the semi-circular wall-part 13 with bottom-plate 14, top-plate 15 and front-plate 4, the wall-part 13 being fastened to the pivot 6. In the front-plate 4 an angular slit 16 is arranged, in which the end of the articulator-axis is guided. In the bearing-case a semi-circular block 17 is positioned by means of the pivots 18, 18 and can be turned round its middle-axis. The block 17 is provided with a handle 19 projecting through a circular slit 20 in the top-plate 15 of the bearing-case.

30 In the top-plate 15 a squeezing-screw 21 (Fig. 1) is arranged which when being turned will touch with its point upon the plate 22 provided on the block 17 and by means of this squeezing-screw the block is held in the required position.

At the inner side of the front-plate 4 two levers 24 are arranged connected together by way of a spring 23. These levers are pressed by the spring against a pin 25 fastened in the plate 4. Each of the two ends of the articulator-axis projects through the slit 16 between the two levers 24 up to the front-plate of the block 17, as shown in Fig. 9. In the zero position the ends of the 45 axis are in contact with the blocks 17 in their middle-axis. The spring 23 always tends to bring about a striking of the pair of levers 24 against the pin 25 and thereby to lead back the appertaining end of the 50 axis to the zero-position. The arm 3 carrying the adjustment-pin 2 serves as carrier for the non-illustrated model of the upper jaw. The ground-plate 26 carrying the stand 8 serves as carrier for the model of the under jaw not shown in the drawing. Upon the fore end of this ground-plate 26 shaped like a plug, a casing 27 is displaceable carrying a right angular plate 28 being inclined at about 30 degrees towards the 55 horizontal plane. The adjustment pin 2 is displaceable in its longitudinal direction on the arm 3. In the zero-position of the apparatus the adjustment pin 2 rests with its point in the middle of the plate 28.

60 The mode of employing the articulator

and the operation of the same are the following.

At first the one of the chewing-moulds obtained with the patient in known manner by the patient's chewing-motion is fastened to the ground-plate 26, the other to the arm 3, and in the plate 28 soft amalgam is carried in. Hereupon the arm 3 with the chewing-mould fastened thereto is moved in such manner along marked guide-grooves 75 over the chewing-mould fastened to the ground plate 26, as the virtual jaw-axis of the patient would be motioned to the right and to the left on his chewing. Thereby the pin 2 engraves a precise curve into the amalgam. Under the influence of the articulator-axis 1 moved by means of the arm 3, the bearing-cases 5, the blocks 17 and the pair of springy levers 24, 24 are brought in a certain position. By means of strong turning 80 the screws 12 and 21, the bearing-cases and the blocks 17 are fixed in this position and thereby the articulator-axis 1 is given exactly that possibility of motion which is proper to the virtual jaw-axis of the 85 respective patient.

Hereupon the chewing moulds are removed from the arm 3 and the ground-plate 26, and the amalgam contained in the plate is allowed to grow stiff. With the aid of the 90 guiding-curve engraved in the stiffened amalgam the individual motion-curves of the jaw can now be reproduced even without the chewing-mould by means of guiding the pin 2 along the curve in the stiffened amalgam. In this way an expedient has been obtained which, by placing the two parts of the artificial sets of teeth in the articulator, offers the possibility of an exact control until the working of the artificial 100 sets of teeth has become so perfect that the teeth afford an exact operation in all jaw-motions which may unconsciously arise.

We claim:

1. In an articulator the combination of 110 the articulator-axis with the bearing- or guide-cases for the ends of the articulator-axis, turnably positioned pivots fastened to the bearing-cases, and squeezing-screws for the fixation of the pivots.

2. In an articulator the combination of 120 the articulator-axis with the bearing- or guide-cases for the ends of the articulator-axis, turnably positioned pivots fastened to the bearing-cases, screws for the fixation of the pivots, a turnably positioned block in each of the bearing-cases and means for the fixation of the blocks being in contact with the ends of the articulator-axis.

3. In an articulator the combination of 125 the articulator-axis with turnably positioned and fixable bearing-cases for the ends of the articulator-axis, an angular slit in the front-plate of each of the bearing-cases, a pair of levers turnably positioned at the 130

front-plate, a pin fastened to the front-plate, and a spring pulling the levers against the pin.

4. In an articulator the combination of the articulator-axis with turnably positioned and fixable bearing-cases, in the bearing-cases turnably positioned and fixable blocks and an arm fastened upon the articulator-axis provided with a displaceable adjustment-pin.

5. In an articulator the combination of the articulator-axis with turnably positioned and fixable bearing-cases, in the bearing-cases turnably positioned and fixable blocks,

an arm fastened upon the articulator-axis 15 with a displaceable adjustment pin and a ground-plate with a supporting-plate for the adjustment-pin displaceable on the supporting-plate.

In testimony whereof we have signed our 20 names to this specification in the presence of two subscribing witnesses.

Dr. CARL RUMPEL.

Professor Dr. HERMANN SCHRÖDER.
